UNITED STATES PATENT OFFICE.

LE ROY W. FAIRCHILD, OF NEW YORK, N. Y.

DESIGN FOR PENCIL-CASES.

Specification forming part of Design No. **11,456**, dated October 7, 1879; application filed September 6, 1879.
[Term of patent 7 years.]

To all whom it may concern:

Be it known that I, LE ROY W. FAIRCHILD, of the city, county, and State of New York, have produced a new and original Design for a Pencil or Button-Hook Case, of which the following is a full, clear, and exact description, reference being had to the accompanying engraved illustration, making a part of this specification.

A is a representation of the complete design, the same being that of a fish with a ring, b, joined to the terminal of the tail, and a tube, d, in the mouth. c is a bead finish at the terminals of the inner and outer tubes of the case.

Further minute description is deemed unnecessary.

The several parts of the case and its ornamentation may be made in different colors or in different shades of the same color.

What I claim as my invention is—

A design for a small-implement case in the external form of a fish carrying a tube in its mouth, and having a ring at the terminal of its tail, substantially as shown and described.

LE ROY W. FAIRCHILD.
